CROQUET MALLET

Walter M. Holdstein, New York, N.Y., assignor to General Sportcraft Company Ltd., Bergenfield, N.J., a corporation of New York

Filed Feb. 11, 1960, Ser. No. 59,360

Term of patent 7 years

(Cl. D34—5)

Fig. 1

Fig. 2

Fig. 3

Fig. 1 is a side elevational view of a croquet mallet showing my new design;

Fig. 2 is an end elevational view;

Fig. 3 is a top plan view;

Fig. 4 is a side elevational view of the design for a croquet mallet shown in Fig. 1, wherein the area between the striking faces on the head is concave rather than cylindrical.

Fig. 5 is an end elevational view of Fig. 4; and

Fig. 6 is a top plan view of Fig. 4.

This application is a continuation-in-part of my copending applications Serial No. D-57,437, filed September 4, 1959 and Serial No. D-57,438, filed September 4, 1959.

The characteristic feature of my design resides in the combination on the croquet mallet disclosed of the specific handle grip in association with a head having striking faces of a noticeably greater diameter than the balance or intervening portions of the head substantially as shown.

I claim:

The ornamental design for a croquet mallet, as shown and described.
